Elbert W. Allen, Belgium, Wis.

Application July 30, 1938, Serial No. 78,983

Term of patent 7 years

To all whom it may concern:

Be it known that I, Elbert W. Allen, a citizen of the United States, residing at Belgium, in the county of Ozaukee and State of Wisconsin, have invented a new, original, and ornamental Design for a Shoe, of which the following is a specification, reference being had to the accompanying drawing, forming part thereof.

In the drawing:

Figure 1 is a perspective view of a shoe showing my new design; and

Figure 2 is a plan view of the same.

The characteristic feature of the design resides in a man's sport shoe comprising a heavy sole and a one piece upper with a broad rounded toe portion, and having a placket laterally offset from the center and downwardly inclining substantially as shown.

I claim:

The ornamental design for a shoe, as shown and described.
